INDUCTION VENTILATOR

Filed Aug. 18, 1928

UNITED STATES PATENT OFFICE

FRANK R. KELLEY, OF PITTSBURGH, PENNSYLVANIA

INDUCTION VENTILATOR

Application filed August 18, 1928. Serial No. 300,479.

This invention relates to an improvement in an induction ventilator cowl.

The ventilator of the present invention constitutes certain additions and improvements 5 in the ventilator illustrated and described in my Patent No. 1,744,476, issued January 21, 1930.

The object of the invention is to provide an induction cowl for a ventilator, which is 10 constructed with walls and a baffle element contoured to give maximum efficiency at low wind velocities.

A further object of the invention is to provide a slight restriction in the throat of an 15 inlet ventilator cowl to increase the efficiency and velocity of the induced air.

In the accompanying drawings Figure I is a schematic view illustrating the tendency of 20 air flow through a substantially horizontal opening under a ventilator cowl and past a baffle plate; this view is given for purposes of aiding in the description of the theory and operation of the present invention; Figure II is a sectional profile of the ventilator cowl 25 of the present invention; Figure III is a plan view of the same; Figure IV is a sectional profile view of a slight modification of the cowl of this invention; Figure V is a sectional view taken on the line V—V of 30 Figure IV; Figure VI is a side elevation of the cowl shown in section in Figure II.

The reference numeral 1 indicates the baffle plate of a relatively simple and unspecialized cowl 2, having the roof 3 formed on a single 35 radius curvature. This illustration shows to advantage the paths in which ingoing air were found, by experiment, to move. The air in moving as wind from the left of the cowl strikes the opening of the same, as indicated by arrows. It will be noted that the edge 4, which, as illustrated in this case, is 40 on a straight line, instead of being curved as it would be in a cowl of circular section, causes the air stream to part. Some air is deflected upwardly over the roof of the cowl, and a portion of the air is deflected downwardly and then upwardly as indicated by the arrows 5. The upper limit of the movement 45 of the ingoing air is defined by the arrows 6, and as indicated by the arrows 7, there is a

region of turbulence, in which no induction takes place. This turbulence robs the air of an appreciable amount of its kinetic energy.

Therefore, it may be understood that the edge 4 causes a downward trend of ingoing 55 air, which effectuates a vena contracta, and which creates a region of turbulence, both of which occur at the cost of overall ventilating efficiency.

Adjacent the upper edge of the baffle 60 plate 1, a similar action takes place, and causes a region of turbulence at 8, which has a further lessening effect on the efficiency of the ventilator.

Figure II shows a sectional view through 65 the cowl of the present invention. In this form the roof and back plate 9 is contoured in section to create a constraining surface for the inflowing air, which conforms to the natural stream line flow of air entering a 70 cowl of this general type; that is, for a cowl having an effectual inlet opening which is in a plane substantially horizontal. This effectual opening lies between the lip 10 and the ridge 11b of the baffle member 11, explained infra, and is bounded on the sides by the outwardly curved side portions 12a. Al-

though it is common to form the openings of ventilators flared, it has been found that the desired results are not accomplished unless the flared portions are formed in a curve 75 continuous with the surfaces adjacent thereto, similar to the manner in which the plate 9 curves smoothly from the lip 10 into the adjacent roof portion 9a. As indicated by 80 the arrows, this curvature eliminates or greatly lessens the vena contracta and the turbulence adjacent said opening. It is

further important from the standpoint of air flow, that the peak 9b of the roof plate 85 should lie approximately over the center line of the cowl as a whole. For the same reason, the portion 9c is curved outwardly and vertically beyond the throat of the ventilator and/or the opening of the downcomer 14. 90

Instead of providing a uniformly vertical baffle member, such as the member 1, the improved cowl has a plate 11 curved to provide a baffle and air deflecting surface. The portion 11a of this plate is inclined inwardly 95 100

from 60 to 80 degrees from the horizontal, and this feature alone was found to give an increase in efficiency. Even slight increases in efficiency are very valuable in natural ventilation because of the low wind velocity with which the ventilator must frequently operate. The portion 11b of the baffle member is curved, as shown, to eliminate the eddy currents, as at 8 in Fig. I. The combination of the improvements above outlined operates to give the ventilator a much greater efficiency.

As may be seen in Figure III, the side plates 12 are out-flared at 12a, as said, to afford an inlet area, relatively wide with respect to its depth, and it may also be seen that all of the plates of the cowl converge to a square section at 13, where the cowl overlies the circular downcomer pipe 14. A so-called spider, well known in the art, is conveniently employed for revolvably mounting the cowl. The spider includes the cross-members 15 for laterally securing a cowl supporting rod 15a within the cowl. Spider members 15b are fixed within the downcomer 14, and these spider members decline toward each other to carry mutually at their lower ends a bearing block (not shown) for supporting pivotally the lower end of the cowl supporting rod 15a. It should be stated, however, that the cowl may be immovably fixed to a downcomer, or it may be mounted to be manually rotated, as is desirable for ship cowls.

Since it is obviously practical to form the cowl in its lower portion 13 to seat over and around the upper edge 14a of the downcomer, it will also be obvious that an inner member should be employed to inwardly overlap this jointure. Experiment has proven that the slightly conical member 16 is the most efficient construction to employ for this purpose. The upper portion 16a thereof is square in section so that it may be riveted in position in the cowl, and the lower edge 16b is circular in cross section to conform to the section of the pipe 14; that is, the member 16 converges downwardly from a square to a circular section.

It has been proven that a member, such as the member 16, having a depth from the portion 16a to the edge 16b equal to at least one half that of the mean diameter of the said member, is more efficient than a cylindrical member. A conical member having the area of its lower opening 70% of the throat area at 16a, and having a relatively great depth, as aforesaid, was found to increase the average discharge 13 per cent over that obtained by utilizing the largest cylinder that could be installed in the cowl throat to serve the same purpose. In fact, a similar conical member having its lower area 30 per cent of that of the throat was more efficient than the said largest cylinder. The conical member

cooperates with the cowl portion of the ventilator to increase the velocity of the induced air, and to increase the overall efficiency of the ventilator.

The modified cowl, shown in Figures IV 70 and V, involves a slightly different baffle element 17, which is mounted in the back and roof plate 9a and the side plates 12b. This baffle element has an inwardly sloping portion 17a, similar to the portion 11a of baffle 11, and also has the portion 17b, generally similar to the portion 11b. The marked distinction between the two baffle elements resides in the additional downwardly and outwardly protruding lip 17c, which serves to form an additional constraining and air inducing surface for the inlet opening of the cowl. Figure V shows in plan the arrangement of conical member 16c, which is identical with the member 16.

Figure VI shows a side elevation of the cowl of Fig. II, and illustrates the pleasing appearance of the structure. It is obvious, however, that the principles of this invention may be employed in a ventilator cowl which is substantially circular in its various cross sections.

What I claim is:

1. An intake ventilator including a cowl, the roof of said cowl projecting forwardly and downwardly in a continuous and reverse curve to a lip, and an inlet opening for said cowl extending inwardly from said lip and beneath said roof, together with a baffle surface disposed inwardly of the cowl and extending upwardly to approximately the horizontal plane of said lip.

2. An intake ventilator including a cowl, the roof of said cowl projecting forwardly and downwardly in a continuous and reverse curve to a lip, and an inlet opening for said cowl extending inwardly from said lip and beneath said roof, together with a baffle member disposed inwardly of the cowl and extending upwardly to approximately the horizontal plane of said lip, said baffle member being formed with a rounded surface at its upper extremity.

3. An intake ventilator including a cowl formed of a roof plate and side plates, the roof plate of said cowl projecting forwardly and downwardly in a continuous and reverse curve to a lip, and an inlet opening for said cowl extending inwardly from said lip and beneath said roof plate, together with a baffle surface disposed beneath said roof plate and between said side plates, said baffle surface extending upwardly to approximately the horizontal plane of said lip, the roof plate and side plates of said cowl diverging part 120 way of their extent to said lip.

4. An intake ventilator including a cowl rotatably mounted and extending downwardly over the upper peripheral edge of a downcomer, and a conical member fixed within

said cowl and extending downwardly past and within the peripheral edge of the down-comer, the height of said conical member being no less than one-half the largest diameter of said conical member.

In witness whereof, I hereunto set my hand.

FRANK R. KELLEY.
